LA FOREST EFAW, OF SEATTLE, WASHINGTON.

CAMPING BED.

Application filed April 2, 1923. Serial No. 629,476.

My invention relates to the art of camping beds, or the like. More particularly, my invention relates to a bed which may be folded into a compact form when not in use.

5 In providing a camping bed a condition which must be met is that the device should be capable of being folded in as compact a form as possible, so that its portability may be facilitated. To this end the bed should 10 not involve a mattress. The comfort ordinarily supplied by a mattress should be approximated by a proper stretching and mounting of the flexible support. A primary object of my invention is to provide 15 such a camping bed, which will not involve the use of a mattress, but which will nevertheless approximate the comfort of such equipment, and which may be folded in a suitably compact bundle to facilitate its 20 portability.

In providing a folding bed which eliminates the use of a mattress, the stretching of the flexible support, such as canvas or the like, is important. Such canvas must be 25 held taut and at the same time sufficiently yielding to render the same comfortable. In meeting this requirement respecting the proper stretching of the canvas member, the camping beds of common practice and design 30 involve a bed rail member extending along the upper edge of the bed from the head to the foot thereof. A primary object of my invention is to provide such a bed without any bed rail extending along said upper 35 edge of the bed, it being my purpose to provide such a bed which will permit of the depression of the canvas member without coming in contact with any laterally disposed bed rail. A further primary object 40 of my invention is to so arrange the parts of said bed rail that the weight superimposed upon the bed will tend to hold the parts of said side rail together by providing 45 for the forces developed in the parts of said rail to act in opposition to each other. Still again, it is a fundamental object of my invention to provide such a bed rail which may be operated as an efficient lever in producing the necessary tautness in the flexible 50 support.

While meeting the above conditions the bed must be of sufficient strength to support relatively great weight. In doing this with a portable bed the number of separate parts 55 must be reduced to a minimum. A primary

object of my invention is to produce a bed of the aforesaid mentioned strength and at the same time involve as few parts and be of as simple a nature as possible.

Moreover, a primary object of my invention is to provide such a bed which will have parts which will assist in keeping the members together when dismounted, and furthermore, I purpose providing such a bed which will at the same time be free of separate 60 parts which may become lost.

The above mentioned general objects of my invention together with others inherent in the same are attained by the mechanism illustrated in the following drawings, the 70 same being merely preferred exemplary forms of embodiment of my invention throughout which drawings like reference numerals indicate like parts:

Figure 1 is a view in perspective of the 75 bed embodying my invention;

Fig. 2 is a view in side elevation with a side member assembled and ready to be moved into position for stretching the canvas member;

Fig. 3 is a view of one end of the side of the same;

Fig. 4 is a view of one end of a side member;

Fig. 5 is a view in perspective of the side 85 of the connector of the side member;

Fig. 6 is a view in detail of the joint of said side rail member in operative position;

Fig. 7 is a view in detail of said side rail joint just after disengagement with the 90 socket of said joint;

Fig. 8 is a view of the side rail member when assembled for storing or transporting said bed embodying my invention; and

Fig. 9 is a view of a modified form of connecting means for a brace member of the 95 side rail.

A bed head 10 and a bed foot 11 that is, supporting members are provided with collapsible legs 12 and 13, respectively. These 100 legs may be mounted by means of a hinge 14 and releasably held in position by brace 15. The bed head and the bed foot are connected by means of a flexible support 16, which may be preferably secured to the said bed head 105 and bed foot by helical springs 17, said springs engaging a rod 18 disposed transversely in the flexible support 16. As herein employed the terms "bed head" and "bed foot" are not intended to indicate any 110

distinction as respects construction, said terms being adopted merely for purposes of description.

The bed head and the bed foot are maintained in spaced relation by means of the side rails 19.

The side rail 19 preferably consists of two braces, 20 and 21. Brace 20 preferably is formed of an upper member 22 and a lower member 23. Upper member 22 may be provided with an end portion 24, having a slot 25 and a shoulder 26. A wing nutted bolt 27 is operatively disposed in said slot 25, whereby said upper member may be clamped to the bed head 10. The upper member 22 and the lower member 23 of brace 20 have a mortised joint provided as respects one end portion of each of said members. A socket 28, (see Fig. 7), is formed by means of a brass binder 29 intermediate the tapering end portion of the ends forming the said mortised joint. A stirrup 30 is pivotally mounted at 31. This stirrup is provided with a slot 32, in which slot pin 33 of the brace member 22 is operatively disposed. The other end of the lower member 23 is cut on the bias to make the same rest flatly in the open stirrup 34. Brace 21 is provided with an end portion 35 similar in construction to end portion 24 of brace 20. The other end of brace 21 is cut on the bias to make the same rest flatly upon the brace 20, with its end abutting against the top part of the stirrup 30.

35. The mode of operation of a device embodying my invention is as follows:

The flexible support 16 is placed under tension by positioning the side rail 19. In positioning the side rail the brace 20 is first installed. This is done by causing the lower member 23 to be extended in approximate alignment with member 22. Thereupon, the mortised end portion of member 22 is forced into the socket 28, and in this wise the mortised ends of the upper member 22 and the lower member 23 are caused to abut. This is made possible by the pin 33 sliding in slot 32. This aligning of the upper and lower members causes the stirrup 30 to bear, as respects its upper portion, upon one side of the brace 20, thereby forming with said brace a bearing for one end portion of brace 21. The other end portion 35 of said brace 21 is clamped to the bed foot 11 precisely as the end portion 24 of the brace 20. This is the approximate disposition of the named parts as illustrated in Fig. 2. When the parts are thus assembled, the lower member 23 may be gripped near its end portion and 60 lifted towards brace 21 and caused to rest in open stirrup 34. By thus forcing lower member 23 towards brace 21 it is manifest that a long lever is provided for stretching the flexible connector 16. In this wise a 65 truss arrangement is provided as respects the

flexible connector 16 and the two braces, as well as between the brace 21 and lower member 23 and leg 13. This manifestly provides a bed which is free of any laterally disposed bed rail.

It has been found that a convenient method of assembling a bed embodying my invention is to turn the same upside down, and thus the lever 23 may be readily pressed downwardly and caused to rest in open stirrup 34. It will be noted that member 22 and brace 21 are put under compression strains, and since brace 21 abuts against the top portion of the stirrup 30, it is manifest that the weight which it sustains operates to force member 23 against member 22, and make tight the joint in the brace 20, so that a firm joint is assured, even after continued use and wear. This joint must necessarily be maintained tight to avoid sagging and untidy appearance in the bed rail, as well as to afford a properly operative device. Contributing to the same end are the inclined or tapering portions of the joint, since any movement longitudinally thereof merely tends to cause member 22 to bear heavily against the brass binder 29. In providing this side rail it is important that the parts be kept of a length which in no instance will exceed the length of the bed head or the bed foot, so that the bundle formed, when rolled up for storage or transporting, will not exceed the length of said bed head or bed foot. Also it is manifest that the more acute the angle formed between brace 21 and member 23, the better is the lever provided thereby for stretching the flexible support. The efficiency of this lever is important. Obviously, the flexible support must be rendered taut and to stretch the large number of stiff helical springs requires considerable force. By providing the efficient lever as herein described the bed may be assembled without great effort.

When the bed above described is to be folded for transportation, manifestly it is only necessary to unclamp the wing nuts on the bolts 27 on the bed head and bed foot, and disengage lower member 23 from the open stirrup 34. Thereupon, lower member 23 is folded back upon upper member 22, and brace 21 is placed against lower member 23 with its end portion projecting within the stirrup 30. Thus these members are assembled for packing. Then the brace members 15 are disengaged from the legs 13, which are then caused to lie flat upon the bed head and bed foot. Thereupon these parts may be rolled within the flexible connector 16 together with the side rails 19, so that a compact bundle is thereby provided.

Thus, there are but three independent parts of the bed embodying my invention, namely, the bed head and bed foot, which are held together by the flexible support 16,

and the two braces 20 and 21. This is a positive requisite of a bed for camping purposes. The parts must be fastened together to as great an extent as possible.

5 Instead of the stirrup connection between the upper member 22 and the lower member 23 of the brace 20, a simple sleeve 36 riveted to member 23 with a socket 37 cast on one side thereof may be provided, but obviously, 10 this does not provide for as ready assembling as the preferred form, nor does it serve to hold the said members together in dismounted position; neither does the sleeve 36 provide for holding the brace 21 as respects 15 its end portion when in position for packing. Also this modified form is objectionable in that the sleeve 36 operates to make member 23 longer than the preferred form. In the above it has been made clear how important 20 it is to keep the parts of the side rail of a length not to exceed the length of the bed head or the bed foot. The preferred length of these parts is to make them about the same length, i. e., brace 21 should be equal in 25 length to members 22 and 23, and thus I provide for the maximum leverage and for the length of parts not to exceed the length of the bed head or the bed foot.

Obviously, changes may be made in the 30 forms, dimensions, and arrangement of the parts of my invention, without departing from the principle thereof, the above setting forth only preferred forms of embodiment. Manifestly, my invention is equally applicable to tables, chairs and stools.

I claim:

1. A device of the character described embodying a bed head; a bed foot; a flexible support extending between said bed head and bed foot; a side rail embodying a two piece brace extending from the top portion of the bed head to the foot of the bed foot; a stirrup joining means for said two piece brace pivotally mounted upon one of said 45 pieces; said stirrup closely embracing the sides of the parts of the two-piece brace; and a brace extending from the top portion of the bed foot to an engaging position with said stirrup, whereby said two piece brace 50 is held in alignment laterally rigid on all sides.

2. A device of the character described embodying a vertically disposed bed-head; a rigid and vertically disposed bed-foot supported on the floor; a flexible support extending between said bed-head and bed-foot; a stirrup carried on said bed-foot adjacent to its lower end; a side rail embodying a two-piece brace extending from the top portion 55 of the bed-head to the foot of the bed-foot and disposed to rest in said stirrup as respects its lower end portion; and a brace extending from the top portion of the bed-head to a point intermediate the length of 60 said first brace upon which it bears, whereby

said first brace may be used as a lever to place said flexible support under tension, said stirrup receiving the downward thrust of said brace.

3. A device of the character described, 70 embodying: a bed head and a bed foot, each having transversely collapsible legs mounted thereon; a flexible support extending between said bed head and said bed foot; a side rail embodying a brace consisting of two members having means for joining the same in line, and stirrup means pivotally mounted on one of said members, whereby said brace extends from the top portion of the bed head to which it is releasably secured, to the foot of the bed foot, said stirrup means also forming a socket on one side of said brace; and a brace releasably secured to the top portion of the bed foot from 75 which it extends to said socket and rests upon said first named brace, whereby is formed a side rail in spaced relation to the lateral edges of the flexible support which is put under tension by said rail.

4. A device of the character described, 80 embodying: a bed head and a bed foot, each having collapsible legs mounted thereon, the legs of said bed foot also having open stirrups disposed thereon; a flexible support extending between said bed head and bed foot 85 and secured thereto by a series of helical springs; a side rail embodying a brace consisting of an upper and lower member, the upper member being releasably secured to said bed head and the opposite end of said upper member having a tapering end portion with a pin disposed near the end of the same, the lower member having a tapering end portion with a stirrup pivotally mounted intermediate said tapering portion, the stirrup having a slot in which the pin of said upper member is operatively disposed, said stirrup forming a socket on one side of said lower member, said lower member having a socket near its end, into which the end portion of said upper member may extend; and a brace releasably secured to the top portion of the bed foot, from which it extends to said socket, whereby said flexible support may be put under tension when said lower member is caused to rest in said open stirrup of said bed foot.

5. In combination with a device of the character described, a side rail embodying a brace consisting of an upper and lower member, the upper member having a tapering end portion; a pin disposed in said end portion; said lower member having a tapering end portion disposed to register with the tapering end portion of said upper member; a stirrup being pivotally mounted intermediate said tapering portion, the stirrup having a slot in which said pin is operatively disposed, said stirrup forming a socket on one side of said lower member,

said lower member having a socket near its end into which the end portion of said upper member may extend; and a brace disposed to seat in said stirrup socket.

5 6. In combination with a device of the character described, a side rail embodying two braces, one of said braces being formed of an upper and lower member, a stirrup joining means for said members, which 10 means is mounted upon one of said members, said means together with one of said members forming a seat for the other of said braces.

7. In combination with a device of the 15 character described, a side rail embodying two braces, one of said braces being formed of an upper and lower member, a socket forming ferrule being mounted on the upper end portion of said lower member; a stirrup 20 joining means for said upper and lower members; said means being mounted intermediate its length upon said upper end portion and forming together with said upper end portion a seat for the second brace, 25 whereby said second brace holds the lower end portion of the upper member securely seated in said ferrule, thereby effecting an alignment of said two members into a brace laterally rigid on all sides.

30 8. A device of the character described embodying a rigid supporting member at each end thereof; a flexible support connecting said supporting members; an open stirrup mounted on one of said supporting 35 members; a side rail consisting of two braces, one brace extending from the top of one supporting member to the bottom of the other and resting as respects one of its end portions in said stirrup, said brace having 40 a socket means located on said brace substantially in the middle thereof and the other brace having one end freely resting

in said socket and the other end connected to the top of one of the supporting members.

45

9. A device of the character described embodying a supporting member at each end thereof; a stirrup mounted on one of said supporting members; a flexible support connecting said supporting members; a side rail consisting of two braces, one of said braces being releasably connected at one end to the top of one of said supporting members and being of a length such that it extends to the bottom of the other supporting member whereby it may rest in said stirrup, said brace having a seat intermediate its length, and a brace releasably secured, as respects one end portion, to the top of one of said supporting members, and the other end disposed to rest on said first brace and being received by said seat whereby said first brace operates as a lever with said second brace as a fulcrum to push apart the supporting members and thereby to put said flexible support under tension, which tension operates to hold said second brace in operative engagement with said first brace.

50

60

65

10. In combination with a device of the character described; a side rail consisting of two braces, one of which is formed of two members, each of which members having tapering, registering end members, said members being of the same length, one of said members having a socket means, disposed on its tapering end portion, and a seat disposed on its upper side; and a second brace of substantially the same length as said members, adapted to have one of its end portions rest on said first brace and be received in said seat.
